UNITED STATES PATENT OFFICE.

EDWARD D. SCHMITT, OF BALTIMORE, MARYLAND, ASSIGNOR TO THE PURE FOOD PROCESS COMPANY, OF BALTIMORE, MARYLAND, A CORPORATION OF MARYLAND.

MECHANISM FOR OPERATING SEALING-HEADS OF JAR-CAPPING MACHINES.

1,129,739.

Specification of Letters Patent. Patented Feb. 23, 1915.

Application filed April 18, 1913. Serial No. 762,148.

To all whom it may concern:

Be it known that I, EDWARD D. SCHMITT, citizen of the United States, residing at Baltimore, in the State of Maryland, have invented certain new and useful Improvements in Mechanism for Operating Sealing-Heads of Jar-Capping Machines, of which the following is a specification.

This invention relates to machines for applying jar caps, and more particularly to a mechanism for operating the sealing heads thereof.

The object of the invention is to provide a mechanism wherein the pressure applied to the cap, to seat the same, upon the jar, will be entirely independent of the pressure applied to the flange of the cap in the crimping operation, and the provision of a means whereby the pressure applied for seating the cap will be predetermined and limited in each sealing operation.

In the drawings—Figure 1 is a side elevation of the machine, with so much of the conveyer mechanism attached thereto as to show the relative position of the sealing heads to the conveyer; Fig. 2 is an end elevation of the machine, parts being in section, Fig. 1, the conveyer being omitted; Fig. 3 is an enlarged sectional view of the lower part of one of the sealing heads; Fig. 4 is a sectional view of the jar support; and Fig. 5 is a broken sectional view of the upper part of the jar, with cap applied, the cap and jar being of the type designed to be operated upon by the machine.

Referring to the drawings, the numeral 1 designates the main frame of the machine, having a bracket 2 at one end, which supports a number of sprocket-wheels 3 that support and guide a conveyer 4. These sprocket-wheels are mounted upon a shaft 5, to the outer end of which is attached a toothed wheel 6, the teeth being successively engaged by the pawl 7 carried by a rocker-arm 8 loose upon the shaft 5, whereby the conveyer is moved with a step by step movement, the movement of the arm 8 being dependent upon an adjustable rod 9 connected with the crank 10 on the outer end of a transverse shaft 11, suitably mounted in the frame. This conveyer is provided at intervals, with a series of cross bars 11', which engage the jars and move them along the upper surface of the frame with a step by

step movement, and the movement is so timed that the conveyer will halt at intervals, so as to permit the jars to remain stationary for a short time upon the bottle supports, and beneath the sealing heads, as will appear. This conveyer mechanism forms no part of the present mechanism, and will not be further referred to herein.

The numeral 12 designates four hollow columns, arranged two on each side of the frame 1. These columns are, as shown best in Fig. 2, arranged in staggered order, so that the sealing heads supported between the columns will be in direct vertical line above the jar supports, and since they and the mechanism carried by them, are duplicated, a description of one will serve as a description of both. Suitably mounted in the frame 1, and parallel with the shaft 11, is a shaft 13. The shaft has keyed thereto, the gear wheel 14 which meshes with a gear wheel 15 mounted upon shaft 16, supported in standards 17, which in turn meshes with the gear wheel 18 on the shaft 11. Driving power is applied to the shaft 16, and through the gear wheel 15 and gears 14 and 18, impart motion to the shafts 11 and 13. The shafts have cranks 19, within the columns 12, and connected with these cranks are pitman rods 20, which are connected with the reciprocating rods 21, which are guided in adjustable threaded bushings 22, and as shown in the front columns of Fig. 2, in dotted lines, the cranks and pitman rods are duplicated on both sides of the frame, so that a uniform reciprocating motion will be imparted to the parts of the sealing head. The dotted lines showing this structure are omitted from the rear columns, to prevent confusion.

Supported by laterally extending arms 22', below the sealing heads, are the jar supports 23. These supports are arranged, one slightly in advance of the other, so as to be directly beneath the sealing heads and directly in line with the conveyer, so that at points of stoppage of the conveyer, the jars will be successively brought to position upon the supports, and below the head parts.

The sealing head is constructed in two main parts, one for applying the pressure to the cap to seat the same and press the gasket therein upon the lip of the jar preliminary to the crimping or locking of the flange of

the cap, and the other for actuating the crimping fingers carried by the head, to indent the flange of the cap into locking engagement with the locking surface of the jar. Pinned to the rods 21, is a lower cross head 24 which centrally supports the outer crimping-member 25 of the sealing head, and above the cross head 24 is another cross-head 26 having sleeves 27 on its ends, through which work the reduced portions 28 of the rods 21. This upper cross-head 26 carries the plunger 29 of the sealing head, which extends into the outer crimping member 25. The plunger is recessed at its under end as indicated at 30 for the reception of the cap and mouth of the jar, and radially arranged within the lower part 31 of the plunger is a series of indenting fingers 32, which comprise two plugs 33 having springs 34 interposed between them, the inner plugs being provided with indenting points 35, which, in the sealing operation, as will be described, are forced simultaneously into engagement with the flange of the cap, to indent it at intervals under, and into locking engagement with the locking surface of the jar. Within the end of the outer or crimping member of the head, is a ring 36, having a cam-surface 37, adapted to be engaged by the outer plugs of the indenting fingers 32 in the sealing operation.

Carried on the tops of the sleeves 27 of the cross head 26, are cups 38 which contain coil springs 39, surrounding the upper reduced portions 28 of the rods 21. These cups are provided with screw-caps 40 having central plugs 41 therein, into which the upper ends of the rods 21 are threaded, which plugs, as will appear from the description of the operation, may move with the rods in the downward movement thereof, which is in excess of the movement of the cross head 26.

The tension of the springs 39 may be varied by adjusting the caps 40 and the distance to which the cross-head 26 may descend may be regulated by the threaded bushings 22, which bushings serve as stops to limit the downward movement of the cross-head, as will appear.

The bottle support comprises a cup 43, in the bottom of which is a washer 44, through which works a rod 45, which has a head 46 which supports the upper telescoping member 47 of the support, and interposed between the head 46 and washer 44 is a sealing spring 48. The lower end of the rod is provided with nuts by which the tension of the spring may be varied, and I provide, in the bottom of each support, a threaded plug 49 having a cup 50 therein, which allows for the movement of the rod. This plug may be removed to gain access to the adjusting nuts and the plug is held in adjusted position by a lock nut 51. Embedded in the

upper member 47 of the support, is a disk of rubber or other compressible material 52, and while I have described one of these bottle supports, it will be understood that there is one for each sealing head.

70

The spring 48 within the support is adjusted for just the pressure that is required and desired to be applied to the cap in seating it on the jar, unassisted by any action of the plunger 29 of the sealing head, which 75 plunger moves down with a positive predetermined unyielding movement, and all the pressure that is put upon the cap is produced by the tension of the springs 48, which, as before suggested, are adjusted for 80 the proper pressure.

In operation, when the shafts 11 and 13 are rotated through the described gears, the rods 21 will, through the pitman rod connections, reciprocating rods 21, and the 85 parts carried thereby, assuming the parts to be in normal position, or in the position shown in Fig. 2, be drawn downward, and in this initial downward movement, both

parts of the sealing-head, that is to say, the outer or crimping member and the plunger, will move downward together, and the plunger will be brought into contact with the cap *a* on the jar, and will continue to apply pressure to said cap in the downward 90 movement of said plunger until the sleeves 27 engage the bushings 22, when the downward movement of the cross-head 26 and plunger 29, will be arrested and at this

time, the spring 28 within the bottle support will have been compressed sufficiently 100 to apply the requisite pressure to the cap, and the sealing gasket therein. No further vertical pressure can then be applied to the cap.

However, it is now necessary to indent 105 or lock the flange of the cap into engagement with the locking shoulder of the jar. This is brought about by a slight excessive movement of the rods 21, which are still

being drawn downward by the crank and 110 pitman connection, and this excessive movement will be against the influence of the springs 39, within the cups 38. Thus,

through the arms 24, pinned to the rods 21, and which arms carry the outer or crimping 115 member 25, the inclined surfaces 37 of the

ring 36 within this member will be brought into engagement with the outer ends of the indenting fingers, causing them to move inward simultaneously, to indent the flange *b* 120 of the cap, and when the cranks have passed a given point, obviously, the rods and parts carried thereby will move upward together,

the movement of the outer crimping member of the head having been slightly in excess 125 in downward movement of the pressure applying plunger.

Having thus fully described my invention, what I claim is:

1. A bottle-capping machine, having in 130

- combination a suitable bottle-support, and a sealing-head comprising two members including cross-heads, columns for supporting said members, one member being adapted to 5 seat the cap on the bottle with a positive, non-yielding pressure, and the other adapted to cause the locking of the cap to the bottle, both members having a simultaneous downward movement, the movement of one being limited upon contact of one of the cross-heads with the supporting columns, and the other having a continuous movement beyond the member having the limited movement.
2. A bottle-capping machine, having in 15 combination, a yieldable bottle-support, and a sealing-head comprising a non-yieldable cap-seating member provided with locking-devices, and a member adapted to act upon the locking-devices, cross-heads operatively connected to the members, columns for supporting said cross-heads, adjustable bushings carried by the columns, the two members being capable of simultaneous movement in a downward direction, the movement of the cap-seating member being limited upon engagement with said bushings and the movement of the other member being continuous beyond that of the said cap-seating member.
3. A bottle-capping machine, having in 20 combination a yielding bottle-support, a non-yieldable cap-seating member carrying locking fingers, a member provided with means arranged to act upon the locking-fingers, means for moving both members simultaneously in a downward direction, means for limiting the movement of the cap seating member before the movement of the other member is completed, whereby the further movement of said other member will cause 25 the acting means of such member to force the locking-fingers into engagement with the cap, and thereby lock the same to the bottle.
4. A bottle capping machine comprising 30 columns, rods reciprocable in the columns, upper and lower cross-heads, the lower cross-head being fixed to the rods, and the upper cross-head being yieldably and slidably connected to said rods, a sealing head comprising two members, one member being fixed to 35 the lower cross-head and the other fixed to the upper cross-head, both members having simultaneous movement downwardly, the movement of one member being limited upon engagement of the upper cross-head with 40 the columns, and the other having a movement continuous with the rods, one member serving to seat a cap on a bottle and the other to cause the locking of the cap to the bottles.
- In testimony whereof I affix my signature in presence of two witnesses.
